GARMENT CLEANING DEVICE

Frank Stuprich, Detroit, Mich.

Application November 9, 1938, Serial No. 239,701

4 Claims. (Cl. 15—40)

This invention relates to the art of cleaning garments and has particular reference to an improved device that is adapted for cleaning cuffs of trousers.

5 One of the objects of the invention is to provide a compact device having a revolving brush whereby lint and the like usually found clinging to the inside of the crease of the trouser may be quickly dispersed the cuffs cleaned perfectly during the various stages of alterations and the like.

While the device is designed primarily for cleaning trouser cuffs it is equally as advantageous in cleaning all kinds of garments as they are altered.

10 Another advantage of the invention is that by its use garments are cleaned automatically, thus effecting a decided saving of time over the old-fashioned method of doing this class of work by hand.

20 Still another advantage of the invention is that due to the compactness of the same and being inexpensive to purchase renders it especially adapted for relatively small tailoring establishments.

25 With the foregoing in mind, it will become readily apparent that the invention possesses further advantages, all of which will be clearly revealed during the course of the following detailed description, illustrated throughout the accompanying drawings, and more fully pointed out in the appended claims.

With reference to the drawings:

Figure 1 is a perspective view of the complete device.

35 Figure 2 is a top plan view of the complete device.

Figure 3 is a side elevation assembly, showing the cover in an open position.

Figure 4 is a front elevation assembly with the cover in an open position.

40 Figure 5 is a longitudinal section taken upon line V—V of Figure 2.

Figure 6 is a sectional view taken upon line VI—VI of Figure 4.

45 Figure 7 is a perspective view of the principal part of the device detached from the electric motor for cleaning purposes.

Figure 8 is a plan sectional view taken upon line VIII—VIII of Figure 3.

50 Figure 9 is a perspective view of the dust receptacle cap.

The invention comprises a unit in which is provided a housing receptacle 1 of the formation as indicated and which is adapted for collected lint, dust and the like, and is provided with removable

cover 2 coacting with opening 1A within the top of said receptacle.

A portion of the housing is extended forwardly as at 3, and referring more particularly to Figure 5, it is clear that portion 3 is directly connected with receptacle 1.

Stand 4 is provided and may be composed of a stamping, casting or otherwise and is adapted to support conventional type electric motor 5 by means of screws 6 where shown, also switch 7 arranged within said stand for the accommodation of motor 5.

Rotatable brush 8 being provided with radial bristles is secured to main shaft 5A of motor 5 by means of internally threaded washer 9 adapted to threadedly engage said shaft, and plain washer 10 with lock nut 11 where shown, and in this manner brush 8 is permanently fixed with the shaft in harmony with motor 5.

With reference to Figure 3, it follows that brush 8 is adapted to rotate in the direction of the arrow in this view, and the trouser cuff is manually held against surface 8A of said brush, hence all lint, dust and the like removed from the cuff is quickly deposited in receptacle 1. See also Figure 5. In the cleaning operation in order to positively prevent lint from flying over brush 8 and into the air within the room in which the device is operated, pocket 12 is arranged as an integral part of receptacle 1 (Figure 3) and all flying lint is thereby arrested at this position, and the accumulation thereof dropping directly into receptacle 1.

Referring now to Figure 8 it follows that portion 3 of the housing is covered as at 13, and opening 14 is provided within covering 13 for passage of the major portion of lint from brush 8 to receptacle 1. Opening 14 is disposed immediately beneath brush 8 and leads directly to receptacle 1.

Cover 15 is provided for brush 8, and is pivoted to the housing by means of hinges 16 where indicated, said cover is locked in a closed position by virtue of latch 17 pivoted to the housing as at 18 and coacting with projected stud 19 secured to said housing and referring to Figure 7 it is clear that gate 20 is provided and is pivoted to cover 15 as at 21, also slot 22 within said cover for engagement of the same with shaft 5A, and by this method the cover is retained in its proper relation with said shaft when motor 5 is in operation.

An important feature of the invention is the means by which receptacle 1 is cleaned of the accumulation of lint therein. This is most effectively accomplished by having the housing unit detachable with respect to stand 4, and in Figure 55

7 it follows that stirrup 23 is permanently secured to the housing where shown and L plate 24 is secured to the top of said stand, also slotted bracket 25 being secured to said housing and 5 is adapted to engage thumb nut 26, and said nut engaging a stud adapted to threadedly engage said stand. In this manner the entire housing unit is quickly removed from stand 4 and the contents remaining in receptacle 1 may be discharged through opening 1A, and following this 10 operation the housing unit is remounted upon stand 4 by the use of the elements just described.

In conclusion let it be understood that the disclosure herewith is merely illustrative of the 15 general principle sought to be protected by Letters Patent, and any modification of the invention made during any probable further development of the same for the market, would fall within the scope of the claims.

20 Having thus fully described my invention, what I claim as new is:

1. In a garment cleaning device, a housing unit, a cover hinged to said housing unit and formed with a clearance slot, and means for 25 holding said cover closed consisting of a gate pivoted to said cover and movable into position across the slot to confine a shaft in the slot and thereby hold the cover closed.

2. In a garment cleaner, a power unit including a rotary shaft and a brush carried thereby for removing dirt from material, a housing defining a dirt-receiving chamber and having an inlet in the path of dirt brushed from the material, a hood carried by said housing for enclosing said brush, said hood being movable into and out of enclosing relation to said brush and having an opening for exposing a portion of said brush, a side wall of the hood being formed with a slot receiving said shaft, and a gate mov-

ably carried by the said side wall of said hood and movable into and out of position across the slot to confine the shaft in the slot and hold the hood closed.

3. In a garment cleaner, a power unit including 5 a rotary shaft and a brush carried by said shaft for removing dirt from material, a housing defining a dirt-receiving chamber and having a front wall formed with a lower inlet opening in the path of dirt brushed from material, a hood 10 for said brush hinged to said housing and having a front recess and an opening spaced from ends of the recess for exposing a portion of said brush in the recess, said hood having a side wall formed with a shaft receiving slot, and a gate 15 pivoted to the said side wall of said hood for movement across the slot into position to block the slot and hold the hood closed with the shaft confined in the slot.

4. In a garment cleaner, a power unit including 20 a base, a motor carried by said base and having a shaft projecting laterally from one side of the base, and a brush carried by the shaft of said motor; a housing removably mounted at the said side of said base and defining a dirt-receiving 25 chamber having a front wall which has its lower portion extending under the shaft and formed with an inlet opening located under said brush, a hood at the front of said housing pivoted to the housing and having its front end formed with 30 a clothes-receiving recess and an opening spaced from ends of the recess and through which a portion of said brush is exposed when the hood is closed, a side wall of the hood confronting the motor being formed with a slot receiving the 35 motor shaft, and a gate movable into and out of position across the slot to confine the shaft in the slot and hold the hood closed.

FRANK STUPRICH.
